ATTORNEY

UNITED STATES PATENT OFFICE.

THOMAS A. REID, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed April 25, 1921. Serial No. 464,308.

To all whom it may concern:

Be it known that I, THOMAS A. REID, a citizen of the United States, and a resident of Pittsburgh, in the county of Allegheny and State of Pennsylvania, have invented 5 a new and useful Improvement in Electric Furnaces, of which the following is a specification.

My invention relates to electric furnaces 10 and particularly to electric-resistance furnaces, and it has for its object to provide an electric-resistance furnace embodying a relatively simple supporting means for a metallic resistor.

15 In practicing my invention, I provide a refractory member with a plurality of slots of substantially L-shape in which a metallic resistor member may be inserted.

In one form of my invention, the refractory members are of such shape and are so located in the walls of the furnace chamber that they cannot be quickly removed therefrom, while, in a modified form, they are of 20 such shape and are so located as to be easily and quickly removed. In either form, the metallic resistor member may be easily and quickly removed and replaced without disturbing the resistor-supporting member itself.

30 In the drawings,

Figure 1 is a view, in vertical section, of a horizontal electric furnace comprising the device embodying my invention;

Fig. 2 is a view, in vertical section on the line II—II of Fig. 1, of a portion of the furnace;

Fig. 3 is a view, in horizontal section on the line III—III of Fig. 4, of a vertical-chamber furnace comprising the device embodying my invention;

Fig. 4 is a view, in vertical section, of a furnace comprising the device embodying my invention taken on the line IV—IV of Fig. 3;

Fig. 5 is a view, in vertical section of a horizontal-chamber electric furnace comprising a modified form of the device embodying my invention;

Fig. 6 is a view, in vertical section, of a portion of the furnace illustrated in Fig. 5, taken on the line VI—VI thereof;

Fig. 7 is a view substantially similar to Fig. 6 and illustrating a different method of supporting the metallic resistor;

Fig. 8 is a view, in end elevation, of the 55 portion of a furnace illustrated in Fig. 7, and

Fig. 9 is an enlarged view, in side elevation, of a portion of a resistor-supporting member embodying my invention.

Referring more particularly to Fig. 1, an electric furnace 10 comprises an outer metallic framework 11 which is provided with suitable supporting members 12. A lining of suitable heat-insulating material is located within the framework 11 and comprises side walls 13, a bottom wall 14 and a roof 15 suitably spaced apart to form a furnace chamber 16. The cover member 15 is preferably made in the form of an arch, 60 and suitable cooperating refractory members 17 and 18 are provided to permit of combining the roof 15 with the side walls 13 to form the chamber 16.

If it is desired to provide resistors at the 75 bottom of the furnace, I may use the type of heating element disclosed in a copending application, Serial No. 449,685, filed by O. A. Colby and myself, on March 5, 1921, and assigned to the Westinghouse Electric & 80 Manufacturing Co., (Case 8720). The heating elements comprise flat refractory plates 19 which are provided, on one surface thereof, with a plurality of integral aligned projections between which may be located the 85 preformed metallic resistor member 20.

The furnace chamber 16 is provided with a high-heat-resisting lining 22 of any suitable or desired form, and a plurality of relatively narrow elongated refractory resistor 90 supporting members 21 located at spaced intervals in the lining 22. Each of the members 21 is provided with a plurality of spaced slots 23, of substantially L-shape, in one surface thereof, the inner end of the slot being 95 slightly enlarged as may best be seen by reference to Fig. 9, for a purpose to be herein-after set forth.

It may be noted that the member 21, with its plurality of slots 23, may be said to have 100 a plurality of symmetrical integral projections in one surface, each of which projections has a single overhanging flange.

In the roof of the furnace, the shape of the members 21 is so modified as to permit 105 of combining two or more members to form a complete self-supporting arch, as is best seen by reference to Fig. 1.

The resistance member 24 comprises a rod or bar of any suitable resistance material, such as nichrome, and is bent to suitable shape and dimensions before being placed in 5 the slots 23. As may best be noted by reference to Fig. 2, the resistor member 24 comprises a number of spaced and substantially parallel extending convolutions with integral end connections.

- 10 The members 21, located at the sides and in the roof of the furnace, are spaced apart a suitable distance which is determined with reference to the metallic resistor member 24 located in the slots 23. It is, of course, apparent 15 that the distance between the successive members 21 may vary in accordance with the thickness of the resistance member itself but it is desirable that the distance between successive members shall be such 20 as to preclude the deformation of the convolutions of the resistor member when the same is heated by an electric current.

If the height of the furnace chamber is slightly greater than the height of the member 21, a suitable refractory brick or block 25 may be provided at each side, as indicated in Fig. 1.

Figs. 3 and 4 illustrate the use of the device embodying my invention in a vertical-chamber electric furnace. A suitable metallic frame 11, and an outer layer 13 of heat-insulating bricks may be provided substantially the same as in the case of the furnace illustrated in Figs. 1 and 2. Spaced apart 30 at suitable intervals inside of the lining 13, are complete circles formed of a plurality of suitably shaped resistor-supporting members 21 each of which is provided with a plurality of slots 23 of substantially L-shape. 35 A lining 22 is located inside of the lining 13 and comprises suitable high-temperature-resisting refractory bricks or blocks. Located in the slots 23 is a suitable resistor member 24 which is formed in substantially the same 40 shape and manner as hereinbefore described in connection with the furnace illustrated in Fig. 1. It is, of course, apparent that the weight of the resistor member 24 is carried by the upper of the two cooperating rings 45 of members 21 which are associated with any one of the resistor members 24. It is, of course, also apparent that the furnace illustrated in Figs. 3 and 4 may be made of any suitable or desired height.

50 Referring more particularly to the modifications illustrated in Figs. 5 and 6, the furnace comprises an outer metallic framework or casing 11 having suitable supports 12. A lining of heat-insulating material in- 55 side of the casing 11 comprises side walls 13, a bottom wall 14 and an arched roof 15, each of which may be formed of suitably shaped and dimensioned bricks or slabs. The side walls, bottom and roof enclose a 60 furnace chamber 16 on the bottom of which

may be located a heating element comprising flat refractory resistor-supporting members 19, hereinbefore described, and a suitable metallic resistor 20. A plurality of spaced resistor members 26 are located inside 70 of the walls 13, the members 26 being substantially of T-shape in lateral cross section and provided, at their inner surface, with a plurality of spaced slots 23 of substantially L-shape, as hereinbefore described in connection with the members illustrated in Fig. 1.

A lining 27 is provided inside of the side walls 13 and comprises a plurality of suitably shaped bricks or blocks of a refractory 80 high-temperature-resisting material, built up in spaced-apart sections, as indicated in Fig. 6. The end bricks of each section are provided with a shoulder portion to cooperate with the overhanging portions of the members 26 to hold them in their operative position. Sufficient clearance may be provided between linings 13 and 27 and between the successive sections of the inner lining and the members 26 to permit of removing 90 them by sliding them vertically upwardly; it being assumed, of course, that the roof member or, at least, a portion thereof, has been removed to permit of thus moving the members 26. Those portions of the outer 95 side walls adjacent the members 26 may be built as separate and easily removable sections. In case it becomes necessary to remove one of the members 26, a part or all of a corresponding removable wall section 100 may be taken out and the member 26 may then be moved horizontally outward.

This construction is also applied to the resistor-supporting members 26 mounted in the roof by building the roof or cover in 105 sections and by providing removable members 28 that are located immediately above the removable members 26. In case it becomes necessary to replace one of the members 26 that are located in the cover member or roof of the furnace, it is only necessary to remove a sufficient number of the blocks 28, after which the damaged member 26 may be moved outwardly through the opening, thus formed, it being assumed, 115 of course, that the resistor member 24 has been removed.

It may be noted that the method of mounting the preformed resistor member 24 in the cooperating members 21 and 26 120 is by first inserting the convolutions in those parts of the slots 23 which extend to the outer surface of the members, then moving the convolutions away from the surface and then substantially downwardly in 125 the case of the horizontal chamber of the furnace, or to either the right or to the left of the vertical center line of the chamber of the furnace.

The convolutions of the resistor member 130

24 are located in the enlarged inner end portion of the slot 23 and it may be noted that the inner portion of the slots 23 are so located that the resistor member 24 is precluded from accidentally being dislodged from the slots as the weight of the resistor tends to maintain it in the enlarged end portion of the slot 23.

In the modifications illustrated in Figs. 10 7 and 8, an insulated auxiliary metal rod 29 is located in the slots 23 in the members 26 and a metallic resistor member 30 of ribbon shape is supported by the insulated rods 29.

If desired, the resistor member 30 may be bent in sinuous form, as illustrated in Fig. 15 7, in order to permit of mounting a greater length of resistor member in a given space. This permits of using a resistor member of 20 greater cross section without decreasing the resistance of the complete heating element below a predetermined value, as may be necessary in connection with an electric supply circuit of a given voltage. The mounting of the resistor members 26 and of the 25 members 28 is substantially the same as hereinbefore described in connection with Figs. 5 and 6. It may be noted that the slot 23 in the member 26 is in a different plane from that illustrated in Fig. 6 and 30 that the member 26 may be made relatively narrow, but these are details of construction that in no wise affect the inventive idea.

The device embodying my invention thus 35 provides a relatively simple refractory resistor-supporting member which may be combined in any suitable or desired locations in the furnace chamber to form a set of cooperating metallic-resistor-supporting means. It may be noted also that, in the 40 modification illustrated, I have provided a quickly removable resistor-supporting means which may be adapted to any size or shape of electric furnace. Further, the device embodying my invention provides a resistor- 45 supporting means which permits the quick insertion and removal of a preformed metallic resistor element, while providing a secure support for the same during the operation of the furnace.

50 Various modifications may be made in the device embodying my invention without departing from the spirit and scope thereof, and I desire that only such limitations shall be placed thereon as are imposed by the prior 55 art or are specifically set forth in the appended claims.

I claim as my invention:

1. An electric heating element for a furnace chamber defined by refractory walls 60 comprising a plurality of spaced-apart relatively narrow, elongated refractory members extending beyond the inner surface of said walls into said chamber each having a plurality of spaced apart transversely extending slots of substantially L-shape ad-

jacent to the inner surface thereof, and a plurality of end-connected convolutions of relatively heavy and self-supporting-resistor material located in said slots and extending openly between said refractory members. 70

2. In an electric resistor-furnace the combination with a plurality of walls spaced apart to enclose a furnace chamber, of a heating means for said chamber comprising a plurality of sets interengaging refractory resistor-supporting members, each having a plurality of transversely extending slots of substantially L-shape therethrough and a substantially self-sustaining resistor located in said slots and extending between said sets 75 of resistor-supporting members and placed in operative position in said slots by being moved in a direction at right angles to the plane of the resistor.

3. An electric resistor-supporting means 85 comprising an elongated refractory member having a plurality of transversely extending slots of substantially L-shape with an enlarged inner-end portion therein.

4. An electric resistor-supporting means 90 comprising an elongated refractory member having a plurality of spaced integral single-flange projections in one surface thereof.

5. An electric resistor-supporting means 95 comprising an elongated refractory member having a plurality of spaced symmetrical integral projections on one surface thereof, each of said projections having a single overhung flange.

6. An electric furnace comprising a furnace chamber provided with side and top walls, a refractory inner lining for said walls consisting of spaced apart sections, refractory resistor-supporting members located in the spaces between said lining sections and projecting into said furnace chamber and having a plurality of slots of substantially L-shape in said projecting portion and a resistor element in said slots. 100 105

7. An electric furnace comprising a plurality of refractory walls and a refractory roof and resistor-supporting members supported respectively by said walls and said roof, each of said members having a plurality of integral single-flange projections 110 115 on one surface thereof, and resistor members supported by said projections.

8. An electric furnace comprising a furnace chamber provided with side and top walls, a refractory inner lining for said walls consisting of spaced-apart sections, each section edge having an overhanging flange, a plurality of refractory members of substantially T-shape located in the spaces between said lining sections and supported 120 125 by said overhanging flanges, each refractory member having a plurality of integral projections of substantially L-shape extending into said furnace chamber, and a resistance element consisting of end-connected convolu- 130

tions supported by said projections of L-shape and being substantially self-sustaining between said projections.

9. An electric furnace comprising a furnace chamber provided with side and top walls, a refractory inner lining for said walls consisting of spaced-apart sections, a plurality of refractory resistor-supporting members located between and supported by 10 said sections and projecting part having a

plurality of slots of substantially L-shape therethrough and a resistance element consisting of end-connected convolutions located in said slots and being substantially self-supporting between said supporting members. 15

In testimony whereof, I have hereunto subscribed my name this 18th day of April, 1921.

THOMAS A. REID.
